7 Claims. (Cl. 104—121)

1

This invention relates to conveyors of the kind comprising parallel rails constituting tracks and carriages which are adapted for engagement with and to travel along the said tracks, for example for the conveyance of articles or goods from station to station during manufacturing processes and the like.

In this connection the invention is intended for application principally without, however, limitation in this respect, to conveyors of this class suitable for installation in boot and shoe factories for the purpose of systemising and expediting the progress of manufacturing operations on and along production lines. Thus, in a conveyor for this particular purpose each of the carriages is usually in the form of a comparatively short wheeled tray or rack, like a small trolley, adapted for holding or supporting one or more series of lasted uppers, complete with lasts, or articles of footwear in various stages of manufacture, or even individual boot or shoe components, and so on. For instance, for the support of lasts, a wheeled rack may be furnished with one or more series of upstanding pegs, whereas other racks or trays may either be provided with work-holding or supporting loops or with receptacles for work in the form of, say, juxtaposed channels or compartments, all as well known to those acquainted with the boot and shoe industry. Accordingly, the invention is not confined to the provision of carriages of any particular form. In use the carriages are propelled, either by hand or automatically, along the tracks from station to station so that the work conveyed can be dealt with progressively by different operators along the production line.

Moreover, the invention has reference particularly to conveyors of the form wherein the tracks are located at or near the backs of the carriages, thereby providing complete freedom of access to the latter. In such a conveyor the two spaced parallel rails of the track or of each track are arranged one above the other so that the track is in a vertical, or substantially vertical, plane. The vertical face of the rail-supporting structure may, for example, have attached thereto superimposed pairs of vertically separated rails suchwise as to provide what may be regarded as an open-fronted conveyor.

Heretofore, conveyors of this form have often required to be arranged closely back to back so that carriages were available for the attention of operatives stationed at opposite sides of the double conveyor.

As, however, such an arrangement is not pos-

2

sible where factory space is strictly limited, the object of the present invention is to provide an improved conveyor which, whilst it has the advantage of a double (back to back) conveyor is adapted for erection and use in a minimum of space.

The invention accordingly consists of a track comprising two spaced rails arranged one above the other, and, mounted to travel along the track, carriages each of which is adapted to be rocked, whilst still engaged with the lower rail, from a position where it is tilted laterally to one side of the track and is handy for loading or unloading by an operative stationed at this side of the track to another position where it is tilted laterally to the opposite side of the track and is similarly handy for loading or unloading by another operative stationed at this opposite side of the track, according to requirements.

20 The idea, as will be appreciated, is to provide a track which is common to operatives stationed at opposite sides thereof and which, moreover, will provide freedom of access to the carriages irrespective as to which side of the track they are located.

In a convenient embodiment of the invention each of the carriages is furnished with longitudinally aligned or alignable wheels engaged with and adapted to run along the lower rail of the track, and is provided with a member or members which are spaced in the lateral direction of the carriage and are adapted for engagement with the upper rail of the said track, the construction and arrangement being such that any one of the carriages can be tilted see-saw fashion laterally of the track to one side or the other with the lower rail as fulcrum, suchwise as to bring the appropriate member or members into contact with the upper rail. That is to say, if the carriage is tilted laterally in one direction the member or members at the appropriate side of the carriage will be brought into contact with the corresponding side of the upper rail, whereas if the carriage is similarly tilted in the other direction the member or members at the other side thereof will be brought into contact with the opposite side of the upper rail. The said members accordingly function not only as stops or abutments to determine the extent of the tilting movement of a carriage in either direction but to assist in supporting the carriage during travel thereof along the track. Thus, as will be understood, a carriage can readily be transferred by 50 45 40 35 30 25 20 15 10 5 a rocking movement about the lower rail from a

position at one side of the track to a corresponding position at the other side thereof.

By the expression "laterally tilted" used in this specification and in the appended claims is meant that a carriage, viewing it from one end, is moved bodily to and fro in a direction transverse to its line of travel and at the same time angularly with respect to a line connecting the upper and lower rails of the track.

The aforesaid combined stop and supporting members on each carriage are preferably in the form of rollers mounted on upwardly directed trunnions, the peripheries of the said rollers being so radiused that the carriage is supportable in an inclined position at the side of the track to which it is moved. In this way, the carriages are effectively presented towards the operatives, and the loading and unloading of the carriages is thereby facilitated.

Each carriage may advantageously be mounted for movement, to one side or the other, relatively to its longitudinally aligned wheels so that during lateral tilting movement of a carriage in either direction its centre of gravity will be shifted to an extent to preclude any possibility of the carriage lifting or "cocking" up when lasts are taken off pegs thereon or work is removed from the work-supporting elements thereon or receptacles therein, as the case may be.

In order that the invention may be more clearly understood and readily carried into practical effect, a specific constructional example thereof as applied to a conveyor having a plurality of superimposed tracks, with carriages on each track, will now be described with reference to the accompanying drawings, wherein,

Figure 1 is a general perspective view of a section of the said conveyor.

Figure 2 is an elevational view of a fragmentary portion of the superimposed tracks as seen from one side.

Figures 3 and 4 are detail elevational views of those parts of Figure 2 ringed round at A and B respectively,

Figure 5 is a fragmentary end elevation of the tracks,

Figure 6 is an end elevational view of one of the carriages per se,

Figure 7 is a detail side view of a portion of one end of such carriage,

Figure 8 is an underside plan view of one of the end frames of the carriage, as seen in the direction of the arrow D in Figure 6, and

Figure 9 is a detail end elevation showing two carriages laterally tilted in respectively opposite directions.

Like parts are designated by similar reference characters throughout the drawings.

Referring to the drawings it will be seen that the improved conveyor includes a plurality of superimposed tracks T each comprising two vertically spaced upper and lower rails 1 and 2 respectively. The upper rail 1 of each track consists of vertically depending flanges of a series of longitudinally aligned lengths or sections 3 of angle iron, whilst the lower rail 2 of the said track consists of upwardly directed vertical flanges of a further series of longitudinally aligned lengths or sections 4 of angle iron. The lengths or sections 3 are secured beneath, and supported from, the outer ends of arms 5 carried by uprights 6 of a conveyor frame. The lengths or sections 4, on the other hand, are secured and supported upon the top sides of the said outer ends of the arms 5. By reason of this arrangement, therefore, the

upper rail 1 of each track T is secured, together with the lower rail 2 of the track above, to the same rail-supporting arms 5. The outer end portion of each rail-supporting arm 5 is welded to one end of an attachment block 7 which is arranged between, and bolted by means of a bolt 8 to, the horizontal flanges of lengths or sections 3 and 4 of angle iron. Moreover, at each location where opposed ends of aligned lengths or sections 3 and 4 abut, these ends are, as shown more clearly in Figure 4, bolted to an attachment block by means of a pair of the bolts 8. At other appropriately spaced locations the lengths or sections 3 and 4 are maintained the correct distance apart by means of spacing collars 9 secured in position by rivets 10 (see Figure 3). The inner ends of the arms 5 may advantageously be welded to the uprights 6, and the latter are furnished with feet 11 (Figure 1) adapted to be secured to the floor.

Each of the carriages C on each track T consists, as shown in Figures 6, 7, 8 and 9, of a pair of spaced end frames 12 connected together at the sides by longitudinal tubular steel rails 13 serving to carry, in the illustrated example, a transversely channelled sheet metal tray 14 adapted to receive shoes in various stages of manufacture. The tray is suitably welded to the rails 13. It is to be clearly understood, however, that the end frames 12, which are a standard production, may alternatively be connected by a member or members serving to carry a series of pegs, work-holding or supporting loops or equivalent. As will be seen more clearly in Figures 6, 7 and 8, each end frame 12 comprises a length of tubular steel bent into the form of an inverted U, and a cross member 15 of angle section the ends of which are welded to the lower portions of the vertical limbs of the U. The inner face of the vertical depending flange 16 of the cross member 15 has welded or otherwise suitably secured thereto a pair of spaced angle brackets 17 which are drilled to provide bearings for an axle 18. This axle is comparatively long and is secured in position by the application to its ends of clips 19. Axially slidably along the axle 18, between two collars 20 mounted thereon, is a small wheel 21 which is peripherally grooved for engagement with and to run along the lower rail 2 of a track T. The inwardly directed flange 22 of the cross member 15 is recessed at 23 to make room for the wheel 21 and permit of axial movement thereof along the wheel axle 18. Each carriage C is therefore provided at each end and at the bottom thereof with a grooved wheel, and when engaged with a rail 2, the two wheels are, of course, longitudinally aligned. Welded or otherwise suitably secured to each end frame 12, near respectively opposite sides of the carriage, are two upwardly directed trunnions 24 through which extend axle pins 25 of rollers 26. The peripheral corners of these rollers are radiused. Moreover, the rollers 26, which constitute the aforementioned combined stop and supporting members, are located well above the end frames 12 to an extent sufficient to enable the two rollers at either side of the carriage to bear against and run along the appropriate side of the relevant upper rail 1 when the carriage is laterally tilted. To permit of initial engagement of the wheels 21 of a carriage with the lower rail 2 of a track T, the appropriate rollers 26 can first be readily inserted between the two rails 1 and 2 of the said track by holding the carriage level, in a horizontal plane. When a carriage is so held the

rollers 26 are disposed beneath and clear of the lower edge of the upper rail 1; it is only when the carriage is tilted that the appropriate rollers are swung upwardly and brought into contact with the upper rail.

One of the two carriages depicted in Figure 9 is shown tilted to the left-hand side of one track, whilst the other carriage is shown similarly tilted to the right-hand side of the next track below. Accordingly, the two rollers 26 at the right-hand side of the upper of the two carriages are shown bearing on and running along the outer side of the upper rail of its track, whereas the two rollers at the left-hand side of the lower carriage are shown bearing on and running along the inner side of the upper rail of the track below. Whenever a carriage C is transferred by a rocking movement from one side of the relevant track T to the other, the wheel axles 18 slide through the grooved wheels 21, this additional component of movement of the carriage changing the centre of gravity of the latter and resulting in a preponderance of weight shifting to that side to keep the carriage steady as previously explained.

To prevent carriages which are travelling at the appropriate side of a track from colliding with the rail-supporting arms 5, the outer end portions of the latter are inclined downwardly somewhat from the track. This will be clear from a consideration of Figure 9, wherein it will be seen that by reason of the inclination of the outer ends of the arms 5, the upper of the two carriages tilted to the left-hand side of its track is clear of those arms 5 serving to support the lower rail 2 of the said track.

If desired, means of any suitable character (not shown) may be provided for automatically effecting transference of carriages from one side of the track to the other. Such means may conveniently consist of guides or cams on the tracks arranged for contact with parts of or on the travelling carriages. Alternatively, guides or cams on the carriages may be adapted for co-operation with the tracks. Similar means may be employed, if necessary, so to move carriages, during travel, as to prevent them from colliding with parts of the conveyor frame.

What I claim then is:

1. A conveyor comprising a track consisting of two parallel rails arranged one above the other, a carriage movable along said track, means on the bottom of the carriage engaging and adapted to run along the lower rail, upwardly directed supporting members at the top of the carriage which are spaced in the lateral direction and are adapted for contact with the upper rail, each supporting member being provided with an upper rail contacting surface and the upper rail contacting surfaces being spaced a substantial distance apart to allow lateral tilting of the location of the center of gravity of the carriage with respect to the lower rail to one side or the other of the lower rail.

2. A conveyor comprising a track consisting of two parallel rails arranged one above the other, a carriage movable along the track, elements on the bottom of the carriage engaged with and adapted to run along the lower rail of the track, upwardly directed supporting members at the top of the carriage which are spaced in the lateral direction and are adapted for contact with the upper rail, each supporting member being provided with an upper rail contacting roller and the peripheries of the upper rail contacting rollers being spaced a substantial distance apart

to allow lateral tilting of the location of the center of gravity of the carriage with respect to the lower rail to one side or the other of the lower rail.

5. 3. A conveyor comprising a track consisting of two parallel rails arranged vertically one above the other, a carriage movable along the track, longitudinally spaced wheels on the bottom of the carriage engaged with and adapted to run along the lower rail of the track, means mounting said wheels for lateral sliding movement relative to the bottom of the carriage, upwardly directed supporting members at each side of the carriage which are spaced in the lateral direction of the carriage and adapted for contact with the upper rail, each supporting member being provided with an upper rail contacting surface and the upper rail contacting surfaces being spaced a substantial distance apart to allow lateral tilting of the location of the center of gravity of the carriage with respect to the lower rail to one side or the other of the said lower rail, the carriage moving bodily sideways in relation to its wheels by virtue of the mounting of the wheels for lateral sliding movement relative to the bottom of the said carriage.

4. A conveyor according to claim 3, wherein the supporting members consist of rollers the axle pins of which are mounted in upwardly directed trunnions provided on the ends of the carriage.

5. A conveyor comprising in combination, a track consisting of two parallel rails arranged vertically one above the other, a carriage movable along the track, transversely disposed axles on the bottom of the carriage upon which are mounted wheels engaged with and adapted to run along the lower rail of the track, the said axles being slidable through the wheels, and the ends of the carriage being provided with upwardly directed parts which are spread in the lateral direction of the carriage and are fitted with supporting rollers adapted for contact as and when required to do so with the relevant side of the upper rail of the track, the construction and arrangement being such that the carriage is laterally tiltable see-saw fashion laterally of the track to either side with the wheels still in engagement with the lower rail and so that the carriage can be transferred as occasion demands from an inclined position at one side of the track determined by contact of the supporting rollers at the appropriate side of the carriage with the opposing side of the upper rail to an oppositely inclined position at the other side of the track determined by contact of the remaining supporting rollers with the opposite side of the said upper rail, the carriage, when tilted to either side as aforesaid, moving bodily sideways in relation to its wheels by reason of the axles sliding through the said wheels so as to change the location of the centre of gravity of the carriage and its contents with respect to the lower rail and shift the preponderance of its weight to that side, for the purpose set forth.

6. A conveyor comprising, in combination, a track consisting of parallel lengths of angle iron arranged vertically one above the other, arms serving to support the said angle irons, uprights carrying the arms, the bottom angle iron being disposed with one flange extending vertically upwards to constitute the lower rail of the track whilst the top angle iron is disposed to present a vertically depending flange constituting the upper rail of the track, a carriage movable along the track, longitudinally spaced and peripherally

grooved wheels on the bottom of the carriage engaged with and adapted to run along the lower rail, upwardly directed supporting members at the top of the carriage which are spaced in the lateral direction and are adapted for contact with the upper rail, and an upper rail contacting roller on each supporting member, the peripheries of said contacting rollers being spaced apart a sufficient distance to allow lateral tilting of the location of the center of gravity of the carriage with respect to the lower rail to one side or the other of the said lower rail.

7. A conveyor according to claim 2, wherein the carriage consists of two end frames connected by longitudinal members serving to carry sup-

5

porting means for articles to be conveyed, the said end frames being fitted with transversely disposed axles upon which the wheels are slidably mounted.
